FRANK ARTHUR REYNOLDS, OF LEWISTON, MAINE, ASSIGNOR OF ONE-HALF TO STEPHEN H. MANNING, OF SAME PLACE, AND HERSCHEL C. PARKER, OF BROOKLYN, NEW YORK.

DOUBLE-ACTING TOOL-DRIVER.

SPECIFICATION forming part of Letters Patent No. 596,790, dated January 4, 1898.

Application filed July 10, 1897. Serial No. 644,135. (No model.)

To all whom it may concern:

Be it known that I, FRANK ARTHUR REYNOLDS, of Lewiston, in the county of Androscoggin and State of Maine, have invented certain new and useful Improvements in Double-Acting Tool-Drivers, of which the following is a full, clear, and exact description.

This invention relates to double - acting tool-drivers, but more particularly to double-acting ratchet-drills.

The primary object of the invention is to simplify the mechanism for operating the tool spindle or shaft and at the same time provide a simple and efficient device which will avoid many of the objections incident to devices of this character as ordinarily constructed.

A further object is to provide a pivoted lever rotatably arranged on the spindle and means connected thereto for transmitting motion to the tool spindle or shaft, so that the tool may be worked by oscillating the lever in various positions with reference to said spindle and to provide a device which may be employed either as a single or double acting tool-driver.

With these and other objects in view the invention consists in the construction and combination of the several parts, substantially as hereinafter described, and then pointed out in the claims at the end of the description.

Referring to the accompanying drawings, forming a part of this specification, in which similar figures of reference designate similar parts, Figure 1 is a general perspective view of one form of device embodying my invention. Fig. 2 is a plan view of the device shown in Fig. 1, the handle of the lever and the drill being partly broken away. Fig. 3 is a longitudinal sectional view, partly in elevation, taken on the line III III of Figs. 2 and 4; and Fig. 4 is a transverse sectional view taken on the line IV IV of Fig. 3.

The spindle or shaft 10 may have one end thereof formed with a socket in which the shank of a drill or other tool or the shank of a mandrel having a tool-holding chuck may be inserted, while the other end of said spindle or shaft may have a screw-threaded bolt

or stem 11 projecting outwardly therefrom, on which may be arranged a suitable pressure-nut, as at 12. This nut may have the usual center adapted to engage a suitable abutment, so that when the nut is rotated 55 the internal threads thereof engaging the threads of the stem or bolt 11 will cause the spindle 10 to advance and force the drill or other tool to its work, though instead of the bolt and pressure-nut a bolt or screw or other 60 pressure device may be provided, the bolt or screw in such case having one end thereof adapted to engage an abutment and the other end screw-threaded and engaging a threaded recess or opening in the spindle, so that when 65 the bolt is rotated the desired pressure may be exerted upon the drill or tool. A pair of opposed ratchet-wheels 13 and 13^a, having their teeth pitched in the same direction, may be secured at or near the opposite ends of the 70 tool shaft or spindle by means of keys or otherwise, or said ratchet - wheels may be formed integral with the spindle, as desired. The parts thus far described may be of the usual or of any preferred construction and 75 are not claimed broadly herein, but only in combination with certain features, which will be hereinafter referred to.

In order to impart rotary motion to the ratchet-wheels and the tool, I may arrange a 80 pair of collars 14 and 14^a so as to rotate upon the spindle or shaft 10, said collars having recesses adapted to partially inclose the ratchet-wheels, which latter serve to retain the collars on said spindle. These collars have lugs 85 or projections 15 and 15^a, respectively, projecting outwardly therefrom and having openings therethrough, in each of which is arranged a pawl 16, which is normally forced inward, so as to engage the teeth of the ratchet- 90 wheel by means of a spring 17, located within the opening in the lugs or projections. The pawls may be polygonal in cross-section or may be partially cylindrical and partially angular, so as to slide in similarly-formed open- 95 ings in the lugs or projections of the collars in order to prevent rotary motion of the pawls, the springs 17 being interposed between plugs, as at 18, fitting the outer ends of the open- 100 ings and the upper ends of said pawls, though

instead of the openings extending entirely through the projections simply a recess may be formed for each pawl and spring, or the pawls may be differently constructed and arranged, if desired. The projections or lugs on the collars 14 and 14^a are engaged by the ends of a lever 19, which is pivoted to a sleeve 20, the latter being journaled on the spindle 10 and interposed between the collars, thus serving as an inner abutment or bearing-surface therefor. This lever may be of any preferred form and arranged upon the spindle or shaft in any desired manner; but I prefer to construct the same as shown, in which the ends thereof are provided with slots 21, fitting the lugs or projections 15 and 15^a, the slots being beveled or relieved, as shown more clearly in Fig. 4, in order that various inclinations of the projections on the collars may be compensated for when said lever is rocked or oscillated on its pivot. The pivot may be in the nature of a trunnion 22, formed on the sleeve 20, on which the lever may be journaled, as shown in Fig. 3, and said lever may be held on the sleeve by means of a washer 23, which is secured to the trunnion 22 by a screw or bolt, as at 24, so as to bear upon the upper surface of the operating-lever, thus permitting the lever to move back and forth parallel with the plane of the drill, so as to rotate the collars 14 and 14^a in opposite directions, or permitting said lever and sleeve to be revolved or oscillated at right angles or around the tool-spindle in order that the collars and operating-lever may be moved simultaneously in the same direction to accomplish the function of an ordinary single-acting ratchet-drill. By this means the parts liable to catch the clothing of the operator are inclosed, and a simple, strong, and efficient mechanism is provided for driving the tool spindle or shaft, thereby avoiding the objections incident to the use of gears and pinions employed on many of such devices.

45 The construction and operation of the invention will be readily understood from the foregoing description when taken in connection with the accompanying drawings.

The drill or tool being arranged in the tool spindle or shaft 10, the pressure-nut brought to bear against a suitable abutment, so as to exert the desired pressure between the end of the drill or tool and said abutment in the usual manner, and the operating-lever 19 moved backward and forward in a plane parallel with that of the tool-spindle and tool, it will be seen if the lever is moved in one direction—as to the right, for instance—that the lever by engaging the lug or projection 15 will rotate the collar 14 in the direction indicated by the arrow in Fig. 2, causing thereby the pawl 16 to engage the teeth of the ratchet-wheel 13, so as to rotate the spindle and tool. During this movement of the lever the opposite collar 14^a, through the lug 15^a, will be rotated in the opposite direction around the tool-spindle, so as to cause the pawl 16^a to slip

over the teeth of the ratchet-wheel 13^a; but when the lever is moved toward the left the reverse action will take place, causing the pawl 16 to slip over the ratchet-wheel 13, while the pawl 16^a engages the teeth of the ratchet-wheel 13^a and causes the tool and spindle to rotate, thus securing practically a constant rotary motion of the drill or tool. Should the device be in such a position that the operating-lever cannot be moved back and forth in a plane parallel with the spindle and tool, the said lever and sleeve may be rotated around or at right angles to said spindle or shaft. In this case the operating-lever 19, engaging the lugs 15 and 15^a, will cause the collars to revolve in the same direction as the sleeve 20, and when moved in one direction will cause the pawls 16 and 16^a to slip over the teeth of the ratchet-wheels; but when the operating-lever is moved in the opposite direction the pawls will be caused to engage the teeth of said ratchet-wheels, thus rotating the spindle at one movement only of the lever. I thus provide a simple and efficient device which may have the lever thereof operated in various positions and which may be employed either as a single or a double acting ratchet-drill or other tool-driver.

It will be understood that various changes may be made in the device—as, for instance, the lugs or projections may be carried by the lever and the collar slotted to receive said lugs, or that the ratchet-wheels may be formed directly upon the tool spindle or shaft; that a plate may be provided so as to cover the exposed outer surfaces of the ratchet-wheels, said plate being either secured to or formed as a part of the shaft or spindle, or may be secured to the collars as desired, and that some of the parts may be dispensed with or others substituted therefor without departing from the spirit of my invention.

Having thus described my invention, I claim as new and desire to secure by Letters Patent—

1. A device of the character described, comprising a tool spindle or shaft, ratchet-wheels having the teeth thereof similarly pitched and rotating with the tool shaft or spindle, a pair of collars rotatably arranged on the shaft and provided with pawls to engage the ratchet-wheels, and a lever pivoted and journaled upon the tool-spindle and having a key-and-slot connection with the collars so as to rotate the same, whereby a single or double acting ratchet drill or tool driver is secured, substantially as described.

2. A device of the character described, comprising a tool-spindle, exteriorly-smooth collars rotatably arranged on the spindle and provided with lugs or projections thereon, an inclosed ratchet-and-pawl connection between each collar and the spindle, and a pivoted lever supported on the spindle and engaging the lugs of the collars so as to rotate the latter in opposite directions when oscillated on its pivot, substantially as described.

3. A device of the character described, comprising a tool spindle or shaft, a sleeve or casing journaled on the spindle, recessed collars rotatably arranged on the spindle, each having a lug or projection, ratchet-wheels arranged in the recesses of the collars and secured to the spindle or shaft, pawls carried by the collars adapted to engage the teeth of the ratchet-wheels, and a lever pivoted to the casing and having slotted ends to engage the lugs of the collars so as to rotate the latter in opposite directions when oscillated on its pivot, substantially as described.

4. A double-acting-ratchet tool-driver, comprising a tool spindle or shaft, a sleeve or casing journaled on the spindle, collars rotatably arranged on the spindle, each having a lug or projection thereon, ratchet-wheels on the spindle, pawls carried by the collars adapted to engage the teeth of the ratchet-wheels, and a lever pivoted to the casing and slotted to

engage the lugs of the collars so as to rotate the latter in opposite directions when oscillated on its pivot, substantially as described.

5. A device of the character described, comprising a tool spindle or shaft, a sleeve or casing journaled on the spindle, recessed collars rotatably arranged on the spindle, each having a lug or projection thereon, ratchet-wheels secured to the spindle and arranged in the recesses of the collars, spring-pressed pawls arranged in the lugs and adapted to engage the teeth of the ratchet-wheels, means for exerting a pressure on the spindle, and a lever pivoted to the casing and having slotted ends engaging the lugs of the collars so as to rotate the latter when oscillated on its pivot, substantially as described.
